Off. 2211

John Moore, of Warren, Mass.
Letter Patent No. 2211-Dated Oct. 31, 1865.
Design for an Inkstand.

The schedule referred to in these Letters Patent and making part of the same.

To all Persons to whom these Presents shall come:

Bethany that I, John Moore, of Warren, in the County of Worcester and State of Massachusetts, have invented a new and useful design for an Ink Bottle or Ink Stand; and I do hereby declare the same to be fully described in the following specification and represented in the accompanying drawings, of which

Figure 1 is a top view, Figure 2 a side elevation, Figure 3 a front view, and Figure 4 a rear elevation of it.

The design has reference to the external surface of the ink bottle and it consists in a cylindrical or slightly tapering mouth tube and a flat dome brand a base a partly prismatic and partly curved or cylindrical in form, that is the portion

of each base is composed of six rectangular faces constituting six of the sides of a regular decagonal prism. The part

of the base is the arc of a cylinder, the arrangement of the dome,

the base and the mouth tube being such as is exhibited in the drawings.

I claim the said design substantially as hereinbefore explained and as represented in the accompanying drawings.

Witnesses:

J. B. Lombard,
W. L. Powers.

John Moore
